UNITED STATES PATENT OFFICE

2,515,082

SEPARABLE GARMENT

Adele H. Evans, Hollywood, Fla.

Application June 4, 1948, Serial No. 31,011

1 Claim. (Cl. 2—70)

2

1 This invention relates to separable and interchangeable garments.

It is an object of the present invention to provide garments in two sections, such as a skirt and blouse and so constructed as to be assembled in use, as a unitary garment.

A further object of the invention resides in providing a plurality of separable garments, all provided with identical male and female separable fasteners, thus permitting the interchanging of garments for purposes of obtaining various style and color combinations.

Another object of the invention is the provision of garments of two or more piece combinations, each provided with a series of separable fasteners, extending entirely around the waist, with the male fastener on one garment and the female fastener on the other garment.

A further object is the provision of slide fasteners upon separable garments, such as a waist and a skirt, with a male fastener on one garment and a female fastener on the other garment, extending around the waist portions of the garments for their major circumference and, when assembled, to be completely hidden from view.

A further and important object of the invention resides in the method of attaching the separable fasteners to the garments whereby alterations of the garment as to waist band sizes are permitted without disturbing the relative positions of the separable fasteners.

Other advantages of the invention will become apparent during the course of the following description, reference being had to the accompanying drawing.

Referring to the drawing,

Figure 1 is a perspective view of a complete separable garment, separated for purposes of illustration.

Figure 2 is a fragmentary enlarged vertical section of the waist band sections of the garments.

Figure 3 is a plan view of the lower garment prior to use and,

Figure 4 is a fragmentary view illustrating a modified form of fastener.

Like numerals are employed to designate like parts throughout the several views of the drawings.

Referring specifically to the drawings, the numeral 5 designates a complete separable garment as a whole, embodying in the present instance, a skirt section 6 and a waist section 7. The waist and skirt may be of any desirable style or material, with the waist terminating in a waist hem 8, around which is secured, as by stitching, one half

section of a completely separable slide fastener of conventional form, as shown at 9. The section of slide fastener 9 extends around the circumference of the waist hem, terminating at the usual side opening of the waist and carries the usual slide of the fastener, as at 10. The side opening of the waist may be provided with any desirable closure means, not shown, such as a slide fastener, snap fasteners or hook and eye fasteners.

The skirt 6 embodies a relatively wide waist band 11, terminating at one side of the garment in a placket opening, as is customary. The placket opening carries any desirable form of closure means, such as the conventional slide fastener 12. The waist band 11 is provided with a companion slide fastener section 13, for interlocking connection to the fastener section 9 carried by the waist.

The section 13 is secured to the inside of the waist band 11, as by stitching and extends around the inside circumference of the band, with one end terminating short of the placket opening. As clearly shown, the slide fastener section 13 is positioned below the top edge of the waist band and, when the garments are assembled through the medium of the sections 9 and 13, the connecting fastener will be obscured and a neatly fitting garment having the appearance of a one piece dress will be presented. It is highly important, that the male and female sections of the slide fastener be identically arranged on all garments for interchangeable use, since to shift the arrangement will defeat the purpose of the invention. It will be observed, by reference to Figure 3, that one end of the fastener section 13 terminates short of the placket opening. The purpose of this is to provide a means for permitting a waist band alteration, as will be essential to the average individual. The area for alterations obviously is held to a minimum in order to avoid a bunched closure to a garment not requiring alterations. Further, the alteration does not disturb the very essential matching relation of the fastener sections 9 and 13.

In Figure 4 has been illustrated a fragment of waist band 14, carrying a modified form of separable fastener on its inner side, embodying a strip of flexible woven tape 15, stitched to the inner portion of the waist band around its inner circumference and provided with equidistantly spaced snap fastener sections 16, either male or female. The fasteners 16 are adapted to be engaged by companion fasteners carried by the waist hem of the upper garment, not shown.

This type of fastener likewise serves to unite two

garments into a unitary structure, having a neat and smooth fitting waist portion.

In the use of the particular garments illustrated, the operator, having put the waist and skirt on, grasps the slide 10 and engages it with the pilot pin of the section 13, sliding the slide 10 around the waist to its terminal end, after which the slide is locked in the conventional manner and the placket and waist opening then closed according to their particular fastening devices. The garment now presents a neat waist band, free from bulges or bumps, so noticeable in the conventional skirt and waist, where the waist carries the usual tail section to be stuffed under the skirt band. The separable fastener eliminates the objectionable waist tail and provides a unitary garment that will not separate or pull apart when in use. The use of the snap fasteners may be found desirable in some cases.

The invention is particularly desirable for use on so-called sun dresses, employing a skirt and a bra top. A jacket or dress top with peplum or a bolero could be used with this combination and various outfits combining different colors or patterns would be interchangeable, thus providing a variety of outfits. The invention is further highly desirable for use upon one or two toned slip combinations, for instance, a white top and a black bottom or, two complete slips may be purchased, one white and one black and the combinations possible equal four different garments. For instance, a dark skirt would require a dark slip, while a white waist would require the white top. The separable feature is particularly desirable from the standpoint of washing or cleaning, enabling the light and dark sections to be separately washed without danger of the dye running, as is the case in the well known black and white slips now in use. The bottom section of the slip could also be used separately as a petticoat.

This invention is also particularly adaptable for use on shorts, slacks, playsuits, etc., with blouse or bra top interchangeable. The invention is particularly desirable where persons budget their clothing expenses, since, as pointed out, the purchase of two complete garments of different design and color will enable an interchange of the waists and skirts to provide four combinations of dresses. As an example of the money saving in a wardrobe, a person could purchase 2 dresses, 2 sun dresses, 1 blouse, 1 skirt, 1 slacks and one shorts and with the many interchangeable combinations possible with such a

wardrobe, a considerable saving in clothing costs would result over the cost of a comparable number of garments.

The present invention is a distinct and valuable advance in the clothing art and is highly desirable from the standpoint of economy in the purchase of wardrobes. The use of the separable fastener on the blouse eliminates the tail material with the resultant saving in manufacturing costs and it is believed that the cost of the slide fastener will be a negligible one, as compared to volume of sales that will result from the manufacture of garments embodying this improved fastener.

It is to be understood that the invention is not limited to the particular garments shown and described, but that it includes within its purview, whatever changes fairly come within either the spirit or the scope of the appended claim.

Having described my invention, what I claim is:

A combination garment embodying an upper and a lower garment, a waist hem formed upon the upper garment and a waist band formed on the lower garment, each of the garments provided with a placket opening in alignment with each other, a separable slide fastener formed in two interlocking male and female sections, one section being stitched to the hem of the upper garment for the major circumference thereof and one section stitched to the inner side of the waist band of the lower garment below its top edge, the second named section extending around the band for the major portion of its circumference, one of the sections terminating short of its corresponding placket opening so as to leave a portion of the waistband between the end of the section and the placket opening free for adjustment purposes.
